CLAIM

The ornamental design for a fluid applicator cap, as shown and described.

DESCRIPTION

FIG. 1 is a perspective view of a fluid applicator cap.

FIG. 2 is a front view of the fluid applicator cap of FIG. 1.

FIG. 3 is a back view of the fluid applicator cap of FIG. 1.

FIG. 4 is a left view of the fluid applicator cap of FIG. 1.

FIG. 5 is a right view of the fluid applicator cap of FIG. 1.

FIG. 6 is a top view of the fluid applicator cap of FIG. 1.

FIG. 7 is a bottom view of the fluid applicator cap of FIG. 1.

FIG. 8 is a perspective view of a fluid applicator cap.

FIG. 9 is a front view of the fluid applicator cap of FIG. 8.

FIG. 10 is a back view of the fluid applicator cap of FIG. 8.

FIG. 11 is a left view of the fluid applicator cap of FIG. 8.

FIG. 12 is a right view of the fluid applicator cap of FIG. 8.

FIG. 13 is a top view of the fluid applicator cap of FIG. 8; and,

FIG. 14 is a bottom view of the fluid applicator cap of FIG. 8.

The evenly broken lines represent parts of the article as well as environmental subject matter of an exemplary container. The dot-dash broken lines represent the boundaries of the claim. None of the broken lines form part of the claimed design.

1 Claim, 12 Drawing Sheets
